US0D1006781S

(12) **United States Design Patent** (10) **Patent No.:** **US D1,006,781 S**
(45) **Date of Patent:** **** Dec. 5, 2023**

(54) **EARPHONE**

(71) **Applicant:** **JVCKENWOOD Corporation,**
Yokohama (JP)

(72) **Inventor:** **Ryotaro Futamura**, Yokohama (JP)

(73) **Assignee:** **JVCKENWOOD Corporation,**
Yokohama (JP)

(**) **Term:** **15 Years**

(21) **Appl. No.:** **29/812,555**

(22) **Filed:** **Oct. 22, 2021**

(30) **Foreign Application Priority Data**

Aug. 6, 2021 (JP) ..... 2021-017155 D

(57) **CLAIM**

The ornamental design for an earphone, as shown and described.

DESCRIPTION

FIG. 1 is a front perspective view of an earphone showing my new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right-side elevational view thereof; and,

FIG. 8 is a left-side elevational view thereof.

The broken lines of the drawings represent portions of the earphone that are not part of the claimed design.
